UNITED STATES PATENT OFFICE.

CLAUD S. GORDON, OF CHICAGO, ILLINOIS.

PYROMETER-SWITCH.

1,320,544.

Specification of Letters Patent.

Patented Nov. 4, 1919.

Application filed June 16, 1916. Serial No. 103,943.

To all whom it may concern:

Be it known that I, CLAUD S. GORDON, a citizen of the United States, and resident of Chicago, in the county of Cook and State 5 of Illinois, have invented certain new and useful Improvements in Pyrometer-Switches, of which the following is a specification.

My invention relates to a push-button 10 type contact switch for making a delicate electric contact, and is particularly adapted for use in connection with pyrometer equipment. It may, however, be used for any electric switching purpose which requires 15 the operation of only one circuit, or any set of circuits at any one time, such as in telephone and alarm systems.

A pyrometer generally consists of a number of thermo couples installed in a furnace 20 or a number of furnaces connected through lead wires to a switching arrangement centrally located, whereby an attendant may read at will the temperature of any one furnace by operating the switching arrangement, which is connected to a common indicating or recording galvanometer.

Switches for pyrometer equipment as heretofore constructed, use either the well-known double-pole double-throw knife 30 switch, or the rotary switch with the contact points in the arc of a circle, and the switch blades pivoted in the center.

When using the double-pole double-throw knife switch, the circuit is closed or broken 35 by throwing the blades from one point of contact to a second point of contact, passing outward through an arc, or in throwing the blades to neutral and throwing a second set of blades or even a third set to a point of 40 contact. In this way some little time elapses between the contacts, which allows the galvanometer needle to return to the zero mark or nearly so, before again coming to rest at the required point. In the more sensitive 45 instruments, it requires an appreciable period of time for the needle to come to rest after the contact is made, thus demanding time and patience on the part of the operator, also causing unnecessary strains on the gal- 50 vanometer movement.

In my invention this is overcome by a mechanism constructed in such a manner that by making a second contact on any circuit, the first contact is automatically 55 broken, at the same instant the second contact is made.

When using the rotary switch, no time elapses between the making of contacts for various thermo couples, but it is necessary to pass through intermediate points to reach 60 the required point of contact. In passing to such intermediate points the switch may pass over a number of points, some of which are connected to low temperature couples and some to high temperature couples, thus 65 causing a great amount of fluctuation before the needle comes to rest on the required circuit.

I have overcome this by constructing the switching mechanism so that by operating 70 any contact it automatically breaks any other contact already made.

The construction of the apparatus invented by me will be better understood by referring to the accompanying drawing, 75 wherein:

Figure 1 is a plan section taken on the line 1—1 of Fig. 2 of the mechanism of the switch with the top cover of the case removed, showing the equipment for three 80 circuits;

Fig. 2 is a vertical section on the line 2—2 of Fig. 1;

Fig. 3 is a vertical section on the line 3—3 of Fig. 2 showing the end of the 85 switching arrangement, and

Fig. 4 is a wiring diagram.

In Fig. 4 of the drawings a simple wiring diagram is illustrated which will enable a better understanding of the installation 90 here referred to. In that figure the thermo-couples which are located in the furnaces are indicated at 10, 11. The galvanometer is indicated at 12, while the switches for closing the necessary contact to complete 95 the circuit are shown at 13, 14, the latter being shown in closed position. It being assumed that one switch is closed and that the workman desires to take a reading from another furnace, it is desirable that the one 100 contact should be broken and the other contact made at exactly the same instant, in order that the galvanometer needle may not be caused to vibrate excessively. The result is secured by the use of the mechanism 105 hereinafter described.

The switch which I have illustrated in Figs. 1 to 3 inclusive comprises a casing 15 having a cover 16 through which the push buttons 17, 18, 19 project. It will be understood that I have shown three switches; that is, means for operating the switches con-

necting three thermo-couples to the galvanometer. The contacts are in the form of spring fingers 20, 21, supported on an insulating block 22 and insulated from each other in a suitable manner. The contact is made by forcing the spring member 20 downward into engagement with the finger 21 by the action of one of the buttons 17, 18, 19, the contact of the lower spherical end 23 of the button or plunger being against an insulating strip 24 on the top of the member 20. While I have referred to the switch as consisting of members 20, 21, it will be understood from the showing that as 15 a practical proposition I provide two of each of said members 20, 21, and that the insulating strip 24 bridges the two strips 20. However, the effect is the same as if only one pair of spring fingers 20, 21, were employed. Mounted in the casing 15 is a transverse shaft 25, to which a plurality of hook members 26 are keyed, one of said members being provided for each switch unit. The hook portion of the member 26 has an inclined upper face 27, the square under face of the hook engaging a metallic wear strip 28, which lies on top of the insulating strip 24. A spring 29, connected to one or more of the members 26, tends to 30 hold the same in the position shown in Fig. 2.

The action is as follows: Assuming the parts in the position shown in the drawings and that it is desired to connect up a switch which is controlled by the button 18, such button is depressed, the end of the switch members contacting the inclined portion 27 of the hook member and oscillating the same as well as all the other hook members, against the tension of the spring 29. As 40 the button is depressed the switch unit controlled by the button 17 is released, because the hook member which holds the same is forced outwardly to a releasing position. The result is that the contacts are broken and remade at practically the same instant. Thus it will be seen that upon pressing any 45 of the buttons, any other buttons which are in a depressed condition are released.

Obviously many expedients may be em-

ployed for securing the same results and 50 modifications which are within the scope of my claims I consider within the spirit of my invention.

I claim:

1. In a device of the class described, in 55 combination, a casing, an insulated support in said casing, a plurality of sets of spring members secured to said support, said members acting as contacts, means extending through the casing for actuating any set of 60 said spring members, a movable member mounted in said casing, a plurality of members secured to said movable member, one of said members being provided for every set of said spring members, and portions of 65 said members being arranged whereby to retain said spring members in contact when in one position and to release said contacting members when another set is moved into contacting position. 70

2. In a device of the class described, the combination of a casing, an insulated support in said casing, a plurality of pairs of spring fingers secured to said insulating support, said fingers acting as contacts, a 75 plurality of buttons projecting through said casing, one button being provided for each pair of spring fingers, a shaft mounted in said casing, a plurality of hooks keyed to said shaft, one hook being provided for each 80 pair of spring fingers, the upper portion of said hook members being inclined or beveled, said inclined portion underlying the end of one of said spring fingers and the end of said spring finger being adapted to underlie the hook when said finger is in depressed or contacted position, the arrangement being such that any of said fingers held in depressed position by said hooks is released upon the depression of any other 85 spring fingers, substantially as described.

Signed at Chicago, Illinois, this 12th day of June, 1916.

CLAUD S. GORDON.
